MAGNET-SUPPORTED DEODORANT CASING

Kaari M. Halvorson, 3224 SE. Alder, Portland, Oreg.

Filed Jan. 16, 1962, Ser. No. 68,327

Term of patent 14 years

(Cl. D16—2)

FIG. 1

FIG. 2

FIG. 3

FIG. 4

FIG. 1 is a top plan view of a magnet-supported deodorant casing, showing my new design.

FIG. 2 is a side elevation.

FIG. 3 is an end view.

FIG. 4 is a section on the line 4—4 of FIG. 2.

The undisclosed side and end of the deodorant casing are substantially the same in appearance as the side and end shown. The bottom of the casing is substantially the same as the top with the exception that the narrow main center rib extends from end to end.

I claim:

The ornamental design for a magnet-supported deodorant casing, as shown and described.
